UNITED STATES PATENT OFFICE.

WILLARD M. WHITE, OF CANTON, CONNECTICUT.

IMPROVEMENT IN CLAMPS FOR MOSQUITO-NET FRAMES.

Specification forming part of Letters Patent No. 147,298, dated February 10, 1874; application filed January 12, 1874.

To all whom it may concern:

Be it known that I, WILLARD M. WHITE, of Canton, Hartford county, Connecticut, have invented an Improved Clamp, of which the following is a specification, reference being had to the accompanying drawings, where—

Figure 1 is a side view of the same. Fig. 2 is a top view thereof. Fig. 3 is a detail face view of the foot hinged to one of the legs of the clamp.

This clamp is specially designed for use with the mosquito-net frame patented to me November 19, 1872, by Letters Patent No. 133,279. The clamp is for the purpose of attaching the extension-rod, which supports the spreader, to the head or foot board of the bed, or the like. It obviously may have other uses.

The invention consists in the combinations of parts set out in the claims at the end of this specification, and what is not therein claimed is supposed, so far as this present invention is concerned, to be old.

The letter *a* indicates one leg of the clamp, and *b* the other. From the former project the mortised lugs *a*¹ *a*², designed to hold the lower joint of the extension-rod. The letter *i* indicates a thumb-screw, bearing against the extension-rod *e*. From the inner side of the leg *a* project two spurs or teats, *f* *f*¹, connected by the cross-pin *f*². (Shown in dotted lines.) The leg *b* has a hook, *b*², taking hold of the cross-bar *f*², thereby pivoting the two legs together. In the top of the leg *b* there is pivoted the swivel *g*, through which runs the thumb-screw *h*, its inner end bearing against the upper end of the leg *a*, whereby the feet on the lower ends of the two legs can be pressed together as hard as desired, so as to grasp the head or foot board *c*. On the lower end of the leg *a* is a broad foot, *s*. On the lower end of the leg *b* is a similar foot, *o*. One or both these feet are hinged or pivoted to their respective legs. I have shown the foot *o* thus pivoted. The purpose of this is to make both the feet flatly embrace the two sides of the board *c*, whatever, within obvious limits, be its thickness, which would not be the case if both the feet were rigidly attached to their respective legs. On the lower end of the leg *b* are

cast two trunnions, *t* *t*. The foot *o* has bearings for these two trunnions, and, being of some malleable metal, as malleable cast-iron, it has four projections, *x* *x* *x* *x*, cast upon it, which are afterward turned down upon the two trunnions, so as to secure the foot to the leg, and yet leave a joint.

Of course, any common method of hinging the leg to the foot would answer the purpose, but this particular manner enables me to cheapen the manufacture of the article. The joint which connects the two legs is also peculiar, and has its advantages. It is obvious that a common joint or pivot would answer the purpose, but the method I describe has two advantages: It enables me to cheapen the manufacture of the article, and it enables me to take the two legs apart without trouble, so that they can be then packed in a smaller space, which is an important matter, as I design the whole mosquito-frame to be very portable, so that it can be packed in the valises and bags of travelers.

I claim as my invention—

1. The combination of the two clamp-legs *a* and *b* by means of the projections *f* *f*¹, cross-bar *f*², and the hook *b*², whereby the two legs are jointed, and yet readily separable, all substantially as shown and described, and for the purposes set forth.

2. The combination of the two clamp-legs *a* *b*, jointed together, and provided with feet *o* *s*, one or both of which are pivoted and adjustable, substantially as shown and described.

3. The leg *b* and foot *o*, provided with a joint consisting of the trunnions *t* *t*, bearings for the trunnions, and the malleable projections *x* *x* *x*, all substantially as shown and described.

4. The combination of the leg *a*, provided with the mortised lugs *a*¹ *a*², and the foot *s*, the leg *b*, pivoted to the leg *a*, and provided with a foot, and the thumb-screw *h*, all constructed and arranged for operation substantially as shown and described.

WILLARD M. WHITE.
